ACCESS LID FOR AN AUTOMATIC CLOTHES WASHER UTILIZING A WASH ADDITIVE DISPENSER, OR SIMILAR ARTICLE**Perry C. McCollom, Jr., Louisville, Ky., assignor to
General Electric Company****Filed Feb. 15, 1973, Ser. No. 332,612****Term of patent 14 years****Int. Cl. D5—05****U.S. Cl. D49—1 A****FIG. 1****FIG. 2**

FIG. 1 is an isometric view of a washer access lid embodying my new design showing a smaller additive dispenser lid in open position and exposing the underlying wash additive dispenser.

FIG. 2 is an isometric view of the same automatic clothes washer lid as shown in FIG. 1 but with the smaller additive dispenser lid in closed position concealing the underlying wash additive dispenser.

I claim:

The ornamental design for an access lid for an automatic clothes washer utilizing a wash additive dispenser, or similar article, substantially as shown.
